United States Patent

Des. 234,469
Patented Mar. 11, 1975

234,469

NAVIGATION INSTRUMENT

John Lindsay, 5050 NE. 178th St.,
Seattle, Wash. 98155

Filed Dec. 4, 1972, Ser. No. 311,794

Term of patent 14 years

Int. Cl. D10—99

U.S. Cl. D10—62

Fig. 1

Fig. 3

Fig. 2

Fig. 4

Fig. 5

Fig. 6

FIG. 1 is a front perspective view of a navigation instrument showing my new design;

FIG. 2 is a front elevational view thereof in a semi-closed position;

FIG. 3 is a left side elevational view of FIG. 2;

FIG. 4 is a right side elevational view of FIG. 2;

FIG. 5 is a bottom edge elevational view thereof;

FIG. 6 is a rear elevational view thereof.

I claim:

The ornamental design for a navigation instrument, as shown and described.
